PORTABLE UNDERWATER PERSONNEL LIGHT

Louis F. S. Bentley, Los Angeles, Calif., assignor to Birns & Sawyer Cine Equipment Co., Inc., Los Angeles, Calif., a corporation of California

Filed Feb. 17, 1969, Ser. No. 15,803

Term of patent 14 years
U.S. Cl. D48—24

FIGURE 1 is a perspective view of a portable underwater personnel light, showing my new design.

FIG. 2 is a perspective view thereof on an enlarged scale.

FIG. 3 is a front elevational view thereof, the cord and battery case being omitted for convenience of illustration.

FIG. 4 is a side elevational view thereof on a greatly enlarged scale; the opposite side is a mirror image of the side shown.

The broken line showing of a human figure in an underwater garment is merely for illustrative purposes.

The cord is broken away in FIGS. 1, 2 and 4 to indicate indeterminate length.

I claim:

The ornamental design for a portable underwater personnel light, substantially as shown and described.
